ASSIGNEES TO OTIS ELEVATOR COMPANY, OF JERSEY CITY, NEW JERSEY, A COR-
PORATION OF NEW JERSEY.

SQUIRREL-CAGE MOTOR.

Application filed May 18, 1923. Serial No. 339,806.

This invention relates to improvements in rotors for multi-speed A. C. squirrel cage induction motors, and more particularly to an improved end ring.

5 In multi-speed A. C. squirrel cage induction motors, it is desirable that the rotor resistance be so proportioned that the required slip and torque shall be obtained for all the different speeds of the motor. It is the object of our invention to produce an end ring electrically so designed that the required rotor resistance is proportioned for all the speeds of the motor.

10 A further object is to produce a rotor that is quiet in operation and also provided with sufficient radiating surface.

We attain these objects by the rotor illustrated in the accompanying drawings, in which,

15 Figure 1 is a plan view of an end ring with radial slots having an open end in the outer periphery of the ring.

20 Figure 2 is a plan view of an end ring provided with arc shaped slots with closed ends.

25 Figure 3 is a plan view of an end ring provided with radial slots and an outer and inner row of arc shaped closed slots, the slots in the inner row being longer than the slots in the outer row.

30 Figure 4 is a view of a portion of an end ring with a straight polar slot.

35 Figure 5 is a longitudinal view of a part of a rotor with the end rings shown in Figure 2 in vertical section.

40 Figure 6 is a perspective view of a part of a rotor with the closed slots in one ring staggered with relation to the closed slots in the other ring.

45 Similar reference characters refer to similar parts throughout the several views.

Referring to the end ring illustrated in Figure 1, the ring, A, has a plurality of teeth 1 formed by radial slots 2 cut in its outer periphery. The ring is adapted to be fastened to rotor bars, 3, one bar to be fastened to each tooth in holes in the ring, as shown in detail in Figure 5. The lips, a, may be omitted if desired. The radial teeth in the ring increase the rotor resistance, since the path between the bars for the currents is around the inner end of the slots, and, therefore, is longer than the shortest line straight path between the ends of the

bars in a ring without the radial slots. As a result of the presence of the radial slots

the largest amount of the current losses in the rotor are placed in the end ring and thereby easy radiation of the heat developed is attained and assured. The resistance of the teeth can be varied by proportioning the slots 2. We have found that the resistance of two adjacent bars and the end ring connection between them, which is termed bar to bar resistance, is an important factor in the amount of noise produced in a squirrel cage motor. The noise is due to high frequency circulating currents and decreases as the bar to bar resistance is increased; therefore, to ensure quiet operation, the bar to bar resistance must be made as high as the desired torque and slip characteristics will permit. In our invention we proportion the teeth to give the maximum allowable bar to bar resistance. In the end ring in the construction illustrated in Figure 1 the current path varies in length depending on which number of poles is in use. Therefore the effective rotor resistance is necessarily greater for the higher speeds than it is for the lower speeds. This construction permits the ring to be designed so that the rotor resistance for each speed may be a compromise between the resistances required for the different speeds, but this may not provide the required resistance for each speed.

45 However with the end ring illustrated in Figure 2, the resistance of the ring itself is such that the required rotor resistance for the various motor speeds is obtained. By required rotor resistance is meant the effective rotor resistance which will give the desired torque characteristics for each speed. The ring shown in the Figure 2 is designed more particularly for a two-speed motor. In the Figure 2 the ring A is provided with arc shaped polar slots 4 on a circle described from the center of the ring. The slots have a definite length, equal to the length of the pole pitch of the largest number of poles or slow speed of the motor. The number of slots is one half of the number of poles. With these end rings when the motor is operating on slow speed no current will flow through the sections 5 of the rings between the slots 4, because all of the sections 5 are of the same potential. All of the slow speed rotor currents in the ring are confined to

- paths through the sections 6, between the top of the slots 4 and the outer periphery of the ring. By properly locating the slots 4 relatively to the outer periphery of the ring the sections 6 can be made to give the required end ring resistance for the largest number of poles or slow speed of the motor. The slots 4, however, do not prevent the high speed rotor currents from flowing through the sections 5 of the ring, as the slots extend over only a part of the pole pitch of the smallest number of poles or for high speed; consequently the entire ring is utilized when the motor is on high speed to give the required resistance for that speed. To obtain substantially the same resistance in all positions of the rotor, the slots 4 in alternate rings are staggered as shown in Figure 6.
- 20 The ring illustrated in Figure 3 is more particularly designed in respect to the arc shaped slots for a three-speed motor. Two rows of slots are shown, slots 4 in the outer row and slots 7 in the inner row. The slots 25 4 fix the current paths for the slow speed, the slots 7 the paths for the intermediate speed and the entire ring the paths for high speed. In the low speed the current paths are confined to the sections 6 in the ring; in 30 the intermediate speed to the sections 6 and 8; and in the high speed to the sections 6, 8 and 9. The location and width of the slots 7 will determine the width of the sections 8. The length of the slots 7 is the same as the 35 intermediate pole pitch, and the number of slots 7 is one half of the number of the poles of the intermediate speed.
- Figure 3 also illustrates an end ring provided with radial slots 3 similar to Figure 1 40 as well as arc shaped slots 4 and 7. The radial slots afford means for proportioning the bar to bar resistance, as has been stated above, and the arc shaped slots afford means for proportioning the resistance of the end ring itself as best suited to give the required 45 rotor resistance for the different speeds.
- The principle of the invention as applied to the arrangement of the slots as illustrated in the rings in Figures 2 and 3 can be used 50 for practically any ratio of speeds. For examples, the end ring illustrated in Figure 2 is designed for a 2-speed motor with a 12-pole slow speed, the number of poles in the high speed being immaterial; and the end ring 55 illustrated in Figure 3 is designed more particularly with respect to the arc shaped slots for a 3-speed motor, with a 12-pole slow speed, a 2-pole high speed and a 4-pole intermediate speed. In the end ring as illustrated in Figure 2 for a 2-speed motor, it 60 may be found that the radiating surface is not enough, and if so, the ring illustrated in Figure 3 can be used for two-speeds wherein the 65 number of slots in the inner row for high speed is determined by the number of

poles for the high speed in question, as has been already explained, and in which ring the current paths for the high speed are confined to the sections 6 and 8, and the additional radiating surface required for high speed is provided for by the sections 9 of the ring, through which no currents flow for either of the two speeds.

This plan of confining the rotor currents in the end rings to definite paths for the various speeds affords means for obtaining the required rotor resistance for all speeds, as has been stated above, and quiet operation, and permits using sufficient radiating surface to radiate the heat generated in the 70 rotor.

The slot 4 is called arc shaped above, but the term arc shape is not designed nor intended to confine the shape of the slot 4 to the shape of an arc, as it is plain that said slot may be straight, for example, as shown in Figure 4.

What we claim and desire to secure by Letters Patent of the United States is:

1. In a multi-speed induction motor of the 80 type wherein the different speeds are obtained by operating with different numbers of stator poles, a squirrel cage type rotor comprising an end ring connected to all the rotor bars and provided with substantially 85 circumferential slots for determining the required rotor resistance for each number of poles.

2. In a multi-speed induction motor of the 90 type wherein the different speeds are obtained by operating with different numbers of stator poles, a squirrel cage type rotor comprising an end ring for the rotor bars, said end ring being provided with substantially 95 circumferential closed slots for determining the required rotor resistance for each number of poles.

3. In a multi-speed induction motor of the 100 type wherein the different speeds are obtained by operating with different numbers 105 of stator poles, a squirrel cage type rotor comprising an end ring connected to all the rotor bars and provided with a series of substantially circumferential closed slots for determining the required rotor resistance for 110 two of said pole numbers, said slots being arranged on a circle having its center on the motor axis and of a number equal to one-half of one of said two pole numbers.

4. In a multi-speed induction motor of the 115 type wherein the different speeds are obtained by operating with different numbers of stator poles, a squirrel cage type rotor provided with means for determining the required rotor resistance for each number 120 of poles, said means comprising an end ring provided with closed slots.

5. In a multi-speed squirrel cage induction motor of the type wherein the different 125 speeds are obtained by operating with dif- 130

ferent numbers of stator poles, means for obtaining the required rotor resistance for each number of poles, said means comprising an end ring connected to all the rotor bars and provided with slots arranged circumferentially.

6. In a multi-speed squirrel cage induction motor of the type wherein the different speeds are obtained by operating with different numbers of stator poles, means for obtaining the required rotor resistance for the largest number of poles, said means comprising an end ring connected to all the rotor bars and provided with a series of equally spaced slots arranged circumferentially.

7. In a multi-speed squirrel cage induction motor of the type wherein the different speeds are obtained by operating with different numbers of stator poles, means for obtaining the required rotor resistance for the largest number of poles, said means comprising an end ring provided with a series of equally spaced slots arranged circumferentially, the number of slots being one-half said largest number of poles.

8. In a multi-speed squirrel cage induction motor of the type wherein the different speeds are obtained by operating with different numbers of stator poles, means for obtaining the required rotor resistance for the largest number of poles, said means comprising an end ring provided with a series of equally spaced slots arranged circumferentially, the length of the slots being equal to the distance between adjacent slots.

9. In a multi-speed squirrel cage induction motor of the type wherein the different speeds are obtained by operating with different numbers of stator poles, means for obtaining the required rotor resistance for the largest number of poles, said means comprising an end ring provided with a series of equally spaced slots arranged circumferentially, the length of the slots being equal to the distance between adjacent slots and the number of slots being one-half said largest number of poles.

10. In a multi-speed squirrel cage induction motor of the type wherein the different speeds are obtained by operating with different numbers of stator poles, means for obtaining the required rotor resistance for each number of poles, said means comprising an end ring provided with series of slots, each series being arranged on a different circle and the number of series being at least equal to one less than the number of different numbers of stator poles.

11. In a multi-speed squirrel cage induction motor of the type wherein the different speeds are obtained by operating with different numbers of stator poles, means for obtaining the required rotor resistance for each number of poles, said means comprising

an end ring provided with series of slots, each series being arranged on a different circle and the number of series being at least equal to one less than the number of different numbers of stator poles, the slots in a series being equally spaced.

12. In a multi-speed squirrel cage induction motor of the type wherein the different speeds are obtained by operating with different numbers of stator poles, means for obtaining the required rotor resistance for each number of poles, said means comprising an end ring provided with series of slots, each series being arranged on a different circle and the number of series being at least equal to one less than the number of different numbers of stator poles, the number of slots in the series on the outer circle being equal to one-half the largest number of poles.

13. In a multi-speed squirrel cage induction motor of the type wherein the different speeds are obtained by operating with different numbers of stator poles, means for obtaining the required rotor resistance for each number of poles, said means comprising an end ring provided with series of slots, each series being arranged on a different circle and the number of series being at least equal to one less than the number of different numbers of stator poles, the number of slots in the series on the inner circle being equal to at least one-half the smallest number of poles.

14. In a multi-speed squirrel cage induction motor of the type wherein the different speeds are obtained by operating with different numbers of stator poles, means for obtaining the required rotor resistance for each number of poles, said means comprising an end ring provided with series of slots, each series being arranged on a different circle and the number of series being at least equal to one less than the number of different numbers of stator poles, the number of slots in the series on the outer circle being equal to one-half the largest number of poles and in the series on the inner circle being equal to at least one-half the smallest number of poles, the slots in each series being equally spaced.

15. In a multi-speed squirrel cage induction motor of the type wherein the different speeds are obtained by operating with different numbers of stator poles, means for obtaining the required rotor resistance for each number of poles, said means comprising an end ring provided with series of slots, each series being arranged on a different circle and the number of series being at least equal to one less than the number of different numbers of stator poles, the length of the slots in one series being equal to the distance between the adjacent slots in said one series and the number of slots in said

- one series being one-half the largest number of poles. 55
16. In a multi-speed induction motor of the type wherein the different speeds are obtained by operating with different numbers of stator poles, a squirrel cage type of rotor provided with means for determining the required rotor resistance for each number of poles, said means comprising an end ring 60 connected to all the rotor bars and provided with circumferential slots and radial slots, the radial slots being arranged to extend between the rotor bars from the outer periphery of the ring. 65
17. In a squirrel cage induction motor, means for obtaining the required rotor resistance, said means comprising an end ring having closed slots, the number of slots being one-half the number of stator poles, 70 said slots being arranged substantially to confine the rotor currents to certain portions of the ring and to cause the remainder of the ring to act as additional radiating surface. 75
18. In a multi-speed squirrel cage induction motor of the type wherein the different speeds are obtained by operating with different numbers of stator poles, means for obtaining the required rotor resistance for 80 each number of poles, said means comprising an end ring having slots, said slots being arranged substantially to confine the rotor currents to certain portions of the ring and to cause the remainder of the ring to act as additional radiating surface. 85
19. In a multi-speed induction motor of the type wherein the different speeds are obtained by operating with different numbers of stator poles, a squirrel cage type of rotor 90 provided with means for determining the required rotor resistance for each number of poles, said means comprising end rings, each end ring being connected to all the rotor bars and provided with slots, the slots in one ring being arranged in a staggered relation to the slots in another ring. 95
20. In a multi-speed induction motor of the type wherein the different speeds are obtained by operating with different numbers of stator poles, a rotor comprising a core 100 carrying active conductors and an end ring for said conductors, said end ring being provided with a series of closed slots, the number of said slots being equal to one-half of one of the pole numbers. 105
21. In a multi-speed induction motor of the type wherein the different speeds are obtained by operating with different numbers of stator poles, a rotor comprising a core carrying active conductors and an end ring connected to all said conductors, said end ring being provided with a series of closed slots arranged on a circle having its center on the motor axis, said slots extending substantially circumferentially of said circle and each of said slots being of a length equal to the distance between adjacent slots. 110
22. In a multi-speed induction motor of the type wherein the different speeds are obtained by operating with different numbers of stator poles, a rotor comprising a core carrying active conductors and an end ring connected to all said conductors, said end ring being provided with a series of closed slots arranged on a circle having its center on the motor axis, said slots extending substantially circumferentially of said circle and being equally spaced, the length of each of said slots being equal to the distance between adjacent slots and the number of said slots being equal to one-half of one of the pole numbers. 115
23. In an induction motor, a plurality of end rings, each end ring being provided with equally spaced closed slots, the slots in one end ring being arranged in staggered relation to the slots in another end ring. 120
24. In an induction motor, a plurality of end rings, each end ring being provided with closed slots, the slots in one end ring being arranged in staggered relation to the slots in another end ring. 125
25. A rotor for an induction motor comprising a core carrying active conductors and end rings connected to all said conductors, each end ring being provided with a series of equally spaced substantially circumferential slots of equal length, said slots being arranged on a circle having its center on the motor axis, the slots in one end ring being arranged in staggered relation to the slots in another end ring. 130

In testimony whereof, we have signed our names to this specification.
